(57) **CLAIM**

The ornamental design for an optical sight mount, as shown and described.

DESCRIPTION

FIG. 1 is an isometric view of a first embodiment of an optical sight mount showing my new design;

FIG. 2 is another isometric view of the optical sight mount shown in FIG. 1;

FIG. 3 is a front elevational view of the optical sight mount shown in FIG. 1;

FIG. 4 is a right side elevational view of the optical sight mount shown in FIG. 1;

FIG. 5 is a rear elevational view of the optical sight mount shown in FIG. 1;

FIG. 6 is a left side elevational view of the optical sight mount shown in FIG. 1;

FIG. 7 is a top plan view of the optical sight mount shown in FIG. 1;

FIG. 8 is a bottom plan view of the optical sight mount shown in FIG. 1;

FIG. 9 is an isometric view of a second embodiment of an optical sight mount showing my new design;

FIG. 10 is another isometric view of the optical sight mount shown in FIG. 9;

FIG. 11 is a front elevational view of the optical sight mount shown in FIG. 9;

FIG. 12 is a right side elevational view of the optical sight mount shown in FIG. 9;

FIG. 13 is a rear elevational view of the optical sight mount shown in FIG. 9;

FIG. 14 is a left side elevational view of the optical sight mount shown in FIG. 9;

FIG. 15 is a top plan view of the optical sight mount shown in FIG. 9;

FIG. 16 is a bottom plan view of the optical sight mount shown in FIG. 9;

FIG. 17 is an isometric view of a third embodiment of an optical sight mount showing my new design;

FIG. 18 is another isometric view of the optical sight mount shown in FIG. 17;

FIG. 19 is a front elevational view of the optical sight mount shown in FIG. 17;

FIG. 20 is a right side elevational view of the optical sight mount shown in FIG. 17;

FIG. 21 is a rear elevational view of the optical sight mount shown in FIG. 17;

FIG. 22 is a left side elevational view of the optical sight mount shown in FIG. 17;

FIG. 23 is a top plan view of the optical sight mount shown in FIG. 17; and,

(Continued)

FIG. 24 is a bottom plan view of the optical sight mount shown in FIG. 17.

The broken lines shown in the Figures are includes for the purpose of illustrating portion of the optical sight mount that form no part of the claimed design.
